(57) **CLAIM**

The ornamental design for a lantern, as shown and described.

DESCRIPTION

FIG. 1 is a top, front, right side perspective view of a lantern showing my new design in a closed configuration;

FIG. 2 is a bottom, rear, left side perspective view of the lantern illustrated in FIG. 1 in the closed configuration;

FIG. 3 is a front side elevation view of the lantern illustrated in FIG. 1 in the closed configuration;

FIG. 4 is a rear elevation view of the lantern illustrated in FIG. 1 in the closed configuration;

FIG. 5 is a left side elevation view of the lantern illustrated in FIG. 1 in the closed configuration;

FIG. 6 is a right side elevation view of the lantern illustrated in FIG. 1 in the closed configuration;

FIG. 7 is a top plan view of the lantern illustrated in FIG. 1 in the closed configuration;

FIG. 8 is a bottom plan view of the lantern illustrated in FIG. 1 in the closed configuration;

FIG. 9 is a top, front, right side perspective view of the lantern illustrated in FIG. 1 showing my new design in an opened configuration;

FIG. 10 is a bottom, rear, left side perspective view of the lantern illustrated in FIG. 1 in the opened configuration;

FIG. 11 is a front side elevation view of the lantern illustrated in FIG. 1 in the opened configuration;

FIG. 12 is a rear elevation view of the lantern illustrated in FIG. 1 in the opened configuration;

FIG. 13 is a left side elevation view of the lantern illustrated in FIG. 1 in the opened configuration;

FIG. 14 is a right side elevation view of the lantern illustrated in FIG. 1 in the opened configuration;

FIG. 15 is a top plan view of the lantern illustrated in FIG. 1 in the opened configuration; and,

FIG. 16 is a bottom plan view of the lantern illustrated in FIG. 1 in the opened configuration.

(Continued)

The dashed broken lines in the figures represent portions of the lantern that form no part of the claimed design. The additional dash-dot-dash lines depict the bounds of the claim and form no part thereof.
